CLAIM

The ornamental design for an absorbent article with a pattern, as shown and described.

DESCRIPTION

FIG. 1 is a perspective view of an absorbent article with a pattern.

FIG. 2 is a front view thereof;

FIG. 3 is a rear view thereof;

FIG. 4 is a right side view thereof;

FIG. 5 is a left side view thereof;

FIG. 6 is a top end view thereof; and,

FIG. 7 is a bottom end view thereof.

The stippling shown in FIGS. 1-2 and 4-6 indicates a contrast in appearance.

The broken lines are included for the purpose of illustrating environment and form no part of the claimed design.

The broken lines shown in FIG. 1 and FIGS. 4-6 illustrate stitching and forms no part of the claimed design.

1 Claim, 5 Drawing Sheets
